US00D611002S

(12) **United States Design Patent**
Azzola et al.

(10) **Patent No.:** **US D611,002 S**
(45) **Date of Patent:** **** Mar. 2, 2010**

(54) **CIRCUIT BREAKERS**

(75) Inventors: **Lucio Azzola**, Bergamo (IT); **Giovanni Frassineti**, Bergamo (IT)

(73) Assignee: **ABB S.p.A.**, Milan (IT)

(**) Term: **14 Years**

(21) Appl. No.: **29/331,873**

(22) Filed: **Feb. 3, 2009**

(57) **CLAIM**

The ornamental design for a “circuit breaker,” as shown and described.

DESCRIPTION

FIG. 1 is a perspective view of an embodiment of a circuit breaker;

FIG. 2 is a front view of an embodiment of a circuit breaker;

FIG. 3 is a right view of an embodiment of a circuit breaker;

FIG. 4 is a left view of an embodiment of a circuit breaker;

FIG. 5 is a bottom view of an embodiment of a circuit breaker;

FIG. 6 is a top view of an embodiment of a circuit breaker;

FIG. 7 is a perspective view of an embodiment of a circuit breaker;

FIG. 8 is a front view of an embodiment of a circuit breaker;

FIG. 9 is a right view of an embodiment of a circuit breaker;

FIG. 10 is a left view of an embodiment of a circuit breaker;

FIG. 11 is a bottom view of an embodiment of a circuit breaker; and,

FIG. 12 is a top view of an embodiment of a circuit breaker.

1 Claim, 12 Drawing Sheets
